UNITED STATES PATENT OFFICE.

CHARLES S. REED, OF HUNTINGBURG, INDIANA, ASSIGNOR TO HIMSELF
AND GARRETT B. BLACKWELL, OF SAME PLACE.

DESIGN FOR A FLOWER-POT.

SPECIFICATION forming part of Design No. 13,896, dated May 8, 1883.

Application filed March 2, 1883. Term of patent 7 years.

To all whom it may concern:

Be it known that I, CHARLES S. REED, a citizen of the United States, residing at Huntingburg, in the county of Dubois and State of Indiana, have invented and produced a new and original Design for Flower-Pots, of which the following is a full, clear, and exact description.

Reference is to be had to the accompanying drawing, forming part of this specification, in which the figure represents a half side view and half sectional elevation of my newly-designed flower pot, or "flower-vase," as it may be termed, the same being applicable either to growing or merely holding flowers.

The article is of circular form transversely at all points throughout its depth, and when viewed in elevation presents a circular base, A, of diminishing tapering configuration in an upward direction, having the appearance of a series of steps, and commencing with a circular lower straight-edge member or band, *i*, mounted by a molding, *c*, having a surface which slopes inwardly in an upward direction, and terminates above in a cavetto or concave, and this molding again mounted by another molding, *d*, of like form as *c*, but of greater depth. Mounted upon this base A is a stem, B, of diminishing taper in a downward direction, and uniting with said base by a concave, *e*. This stem terminates above in an overhanging head-piece or cup, C, which is ornamented externally in regular order, one above the other, with a lower fillet, *f*, a convex or rounded molding, *g*, a flat or straight cylindrical surface, *h*, a convex molding, *i*, another flat or straight cylindrical surface, *h'*, a band, *k*, a cyma reversa, *l*, a convex molding, *m*, a partially-rounded and partially upwardly and inwardly sloping member, *n*, an

outwardly and upwardly sloping surface, *o*, a convex molding, *r*, and a quarter-rounded upper member, *s*.

I claim—

1. The design for the base A of a flower pot or vase, the same consisting of a bottom straight-edged member, *b*, and the stepped members *c d*, each of the latter members having an upwardly-inclined tapering surface terminating in an abrupt concaved surface, as shown and described.

2. The design for the base and stem of a flower pot or vase, the same consisting, as to its base, of a circular straight-edged member, *b*, and the stepped members *c d*, each of the latter having an upwardly-inclined surface terminating in a concaved surface, and of a stem, B, with a downwardly-diminishing taper, and a concavity, *e*, at its lower end, as shown and described.

3. The design for the head-piece or cup C of a flower pot or vase of circular form, consisting of the several members and surfaces *f*, *g*, *h*, *i*, *k*, *l*, *m*, *n*, *o*, *r*, and *s*, arranged in relation with each other to give an ornamental configuration to the exterior of the cup, as herein shown and described.

4. The design for a round flower pot or vase herein shown and described, the same consisting of a stepped vase, A, composed of members *b*, *c*, and *d*, a stem, B, of diminishing taper in a downward direction, and an overhanging head-piece or cup, C, ornamented externally with flat, curved, and sloping members, arranged in relation with each other and around the cup as specified.

CHARLES S. REED.
